BRIQUETTE PRESS

Worth C. Goss, Seattle, Wash., assignor to William A. Carlisle, Sr., Seattle, Wash.

Application February 24, 1939, Serial No. 258,293

4 Claims. (Cl. 18—5)

This invention relates to improvements in presses, and has reference more particularly to presses for the formation of briquettes from finely divided, or comminuted cellulose material, particularly material that is formed from straw, dried corn stalks, hay, alfalfa, etc.; the present machine being designed particularly for the briquetting of material derived from straw and cornstalks, but which may be made suitable for briquetting materials derived from any of the above mentioned, as well as other materials, including that derived from wood waste.

To impart a better understanding of the present invention and its advantages over machines heretofore used, it will here be explained that in the briquetting of any finely divided material, such as is herein contemplated, there is the vital problem of expelling the air therefrom, especially that air which is contained in the particles or in the interstices between the particles of material when received in the mold for compression. The necessity for the expelling of air in the briquetting operation is by reason of the fact that any air that is trapped, or retained in the material, operates to give the finished product a certain degree of sponginess or looseness. Furthermore, by reason of the tendency of expansion of air entrapped under compression, it is not possible, when briquetting pressure is removed, to obtain the desired solidity or unity, or to accomplish that desired permanent binding together of the particles of material that will insure the briquette against deterioration in storage, nor will it be possible to obtain the desired results from the standpoint of the briquette being a long burning and efficient fuel.

Solidity and unity of the briquetted product is the vital and essential factor in the manufacture of such fuel, and it has always been a problem in this industry just how to most effectively and satisfactorily unify the comminuted material. Prior art along this line will disclose many different treatments of the material: the application of heat; the use of binders of various kinds; the addition of moisture to insure unity, but for those materials above contemplated, in the manufacturing of briquettes, it is now quite well established that no moisture, or adhesive binder need be mixed with the material to obtain the desired results provided that all air can be expelled from the material and sufficient pressure applied in the briquetting operation to unite the particles of comminuted material in a single, solid piece.

In my copending application, filed on Dec. 13,

1937, under Serial No. 180,376, I have disclosed an impact press and the use of a high vacuum for withdrawal of air from the material to be briquetted as it is advanced to the briquette molds. The mechanism shown in that application provides means for effecting an initial compression of the material, for displacement of air from between the particles, and it utilizes the high vacuum for extracting that air which is not expelled from the material by this initial compression which takes place in a slotted feed tube. While this means and method shown is entirely satisfactory from the standpoint of air extraction, it does, however, necessitate a very heavy machine, and one not adapted for use as a portable unit. Therefore, it has been the principal object of this invention to provide a briquetting press of a portable character, capable of forming briquettes under extreme pressure, into solid unity and free of air and not requiring use of high vacuum chambers or extreme vacuum producing devices in obtaining these results. As vacuum pumps are available which produce a vacuum of moderate proportions; for example, up to and including twenty-four inches of mercury, which are quite inexpensive and light, it is considered practicable for one modification of the machine under discussion at the present time, to incorporate the use of one of these low vacuum pumps as a means of reducing the air included in the comminuted material to be briquetted, and the remaining air being excluded by means hereinafter described.

It is also an object of this invention to provide an improved type of press, wherein a reciprocating ram advances definite charges of material into a compression tube and there forms them into briquettes; and wherein said compression tube comprises a plurality of longitudinally extending, segmental bars, slightly spaced to provide narrow slits between them for escape of air, as expelled from the material delivered under pressure of the ram.

A further object of the invention is to provide a novel forming tube with which there is associated a novel form of clamp device that operates automatically, under control of the briquette forming ram for holding the tube at one diameter while the material is being compressed therein into a briquette, and then to allow a slight expansion of the tube, thus to somewhat relieve the frictional pressure between the briquette and tube wall, thus to permit, without requiring excessive power input, advance-

ment of the column of briquettes in the tube toward its discharge end.

Further objects of the invention reside in the details of construction of the compression tube and clamp and devices for synchronizing the action of the clamp with travel of the forming ram.

Still further objects of the invention reside in the details of construction of various parts of the machine, their combination and mode of operation as will hereinafter be fully described.

In accomplishing these and other objects of the invention, I have provided the improved details of construction, the preferred forms of which are illustrated in the accompanying drawings, 15 wherein—

Fig. 1 is a longitudinal section, in a vertical plane, of a briquette press embodying the present invention.

Fig. 2 is an enlarged cross section on the line 20 2—2 in Fig. 1, showing the slotted feed tube.

Fig. 3 is a cross section of the forming tube and clamp on line 3—3 in Fig. 1.

Fig. 4 is a plan view of the machine.

Fig. 5 is a vertical cross section on line 5—5 25 in Fig. 1.

Fig. 6 is a vertical cross section of the machine on the line 6—6 in Fig. 1, particularly illustrating the hopper and feed mechanism.

Fig. 7 is an enlarged sectional detail of the 30 clamp control valve mechanism and the clamp.

Fig. 8 is a cross sectional detail indicating the travel of the forming ram with reference to the formation of the briquette and release of the clamp.

Fig. 9 is a cross sectional view of the compression zone of the briquette forming tube, particularly illustrating a steam jacket applied thereto.

Referring more in detail to the drawings—

In Fig. 1, I have shown, in a diagrammatic manner, a preferred form of machine embodying the present invention, and especially adapted for the briquetting of straw, or the like; it being understood that the material to be briquetted, prior to its being brought to this machine, is reduced to a comminuted condition by any suitable means.

The present machine comprises a hopper 1 into which the comminuted material of a selected kind, which may be referred to as straw, is delivered from a supply tube 2. The hopper is mounted upon the upper end of a vertical delivery tube 3, which, at its lower end, opens into a horizontal forming or pressure tube 4, later described in detail.

The vertical tube 3 is rectangular in cross section, as noted by the cross sectional view in Fig. 2, and, as seen, is relatively narrow in its cross sectional width as compared to its cross section length in the direction of the tube 4.

Mounted above the hopper 1 and coaxially, aligned with the tube 3, is a vertically reciprocal feed ram operable to press charges of straw from the hopper 1 into the upper end of delivery tube 3. This ram comprises a rod 6 mounted for reciprocation in a fixed guide bearings 7—7'.

At its lower end, the rod 6 mounts a shoe or pad 6a which serves, when rod 6 is downwardly actuated, to press charges of straw downwardly 70 into the delivery tube 3; these charges being advanced progressively to the forming tube 4.

The rod 6 is operatively connected at its upper end, as will later be described, with a driven crank shaft 8 and operates in timing with move-

ments of a briquette forming ram, to advance charges of material into the forming tube 4.

It will be understood that with the downward travel of the feed rod 6, the loose straw directly under the shoe 6a in the hopper will be somewhat compressed and some of the air thus displaced therefrom into the open by reason of the closer packing of the material. Furthermore, it will be understood that, as the material is advanced into the upper end of tube 3, additional air will be displaced therefrom, and that the further the material is advanced downwardly in the tube, the greater will be its compression and the more will be the percentage of air displaced therefrom.

In order that the maximum amount of air may be displaced from the material in this action of feeding it into the tube 4, the tube 3 is formed with a plurality of air escape slits 10 lengthwise thereof, relatively close together, and extending from the hopper 1 to the tube 4, as seen in Figs. 2 and 8.

The slits 10 are quite narrow in order to prevent any material amount of the straw being pressed therethrough and, as seen in Fig. 2, they are somewhat flared toward the outer side of the tube to allow whatever straw that does escape, to fall freely and not clog the slits. Air that is displaced by reason of pressure on the straw or material in the tube 3, finds its escape through these slots as the charges are advanced downwardly, the effect being that on entering the tube 4, the charges of material are so tightly compressed as to be substantially free of air.

The briquette forming tube 4 is relatively long and is horizontally disposed. At one end it is supported by a housing 11, and at its other end by a clamp 12, later described in detail. At the left-hand end, as seen in Fig. 1, the tube 4 reciprocally contains a briquette forming piston or ram 13, the inner end portion of which reciprocates through the distance spanned by the bracket designated in Fig. 8 by character T; its opposite limits of travel being designated more particularly by the lines a and b respectively. The tube 4 receives the material directly from the tube 3, and it will be noted by reference to Fig. 6, that the diameter of the tube 4 at the point of connection with tube 3, corresponds to the width of tube 3, so as to receive the column of material advanced downwardly in tube 3 without any resistance.

The ram or piston 13 has a flat inner end surface 13' lying in a plane at right angles to its axis. At its outer end, the ram has operative connection, through the mediacy of a link 14, with a crank arm 15 fixed on a rotatably driven cross shaft 16, mounted in a housing 11a. Shaft 16 is driven by a gear 17, which, in turn, is driven by a relatively small gear 18 on a driven shaft 19. Shaft 19 preferably would be equipped with a fly wheel 20 to insure steady operation, and for other reasons which are obvious.

That part of tube 4 at the right of the feed tube 3, as seen in Fig. 1, is formed by a plurality of separate, longitudinally extending segmental bars 4a, 4b, 4c and 4d, shown in Fig. 3, which are arranged to form a tubular mold and a guideway for the column of briquettes formed therein by the action of the ram or piston 13. At a point near to, or at the junction with tube 3, these bars are bound together by means of a pair of spaced, encircling collars 22—22', which hold the tube against diametrical expansion at that point. At the delivery end of the tube, the segmental bars

are enclosed within the clamp 12. This clamp comprises a metallic collar or sleeve 23, which contains the tube 4 therein with slight clearance to permit slight diametrical expansion when the clamp is released. The collar 23 has its inner surface recessed to provide a shallow, relatively wide, inwardly facing channel 23' encircling the tube 4. Fitted in collar 23 is a metallic sleeve 24 welded along opposite ends to the sides of the channel 23' thus to provide a liquid-tight, annular chamber 25 between the sleeve and collar. This chamber 25 is connected by means of a pipe 26, with a valve housing 27, which, in turn, is connected through a pipe 28 to a source of hydraulic pressure medium.

The valve housing 27 contains a cylindrical bore 30 in which a valve piston 31 is reciprocally contained. This valve is normally held in "open" position by the pressure of a coiled spring 32 held by a cage 33 and pressing against one end of the valve piston. A collar or shoulder 31' limits travel of the piston toward "open" position.

As will be noted by reference to Fig. 7, the valve piston 31 has an encircling channel 34 therein, and when the piston is in "open" position, the channel 34 registers with the openings 26' and 28' through which pipes 26 and 28 are connected, with the bore 30; thus, through the housing, to provide a connection between the source of hydraulic pressure medium and the clamp chamber 25. It will be noted that the channel 34 only partially opens the port 28', as will be explained later. When the valve piston is actuated to "closed" position, it closes the opening 28' to pipe 28 and thus cuts off the application of pressure medium to the clamp chamber, and at the same time, opens a relief outlet for the pressure medium in the clamp chamber. This outlet 38a is provided through a pipe connection 38, opening just after the valve piston 31 closes the port 28'. This arrangement provides that as the forming ram 13 travels back, after forming a briquette, the valve piston 31 will open the port 28' partially, and the pressure will build up in the annular chamber 25 during this time. It is to be understood that when the valve 31 is in "closed" position, the channel 34 opens to both ports 26' and 38', opening into pipes 26 and 38, thus to relieve the pressure in the clamp chamber 25 through the valve housing.

It is to be explained now that the sleeve 24 covering the clamp chamber 25 is of a flexible nature, and, under the application and relief of pressure in chamber 25, operates somewhat as a diaphragm. When pressure is applied in the chamber 25, the sleeve is flexed inwardly; that is, toward the forming tube 4, and thus operates to grip and hold it against expansion from its smaller diameter. However, when the pressure is relieved from the clamp, the tube expands to its greater diameter by reason of internal pressure, whereby the friction is somewhat relieved from the column of briquettes therein.

The valve housing 27 in this instance is located close to that end of tube 4 that contains the ram 13 and is supported by a bracket 45, coaxially parallel with the tube 4. Fixed to the ram 13 is a depending arm 46 having a horizontally turned end portion 47 adapted to engage against the extended end of the valve piston 31, just prior to the ram reaching the end of its briquette forming stroke, as will later be fully explained, thus to shift the piston valve 31 to "closed" position whereby to cut off pressure through pipe 28 to the clamp chamber 25 and open the relief 75

therefrom so that during the final travel of the ram 13, the holding friction on the sides of the column of briquettes in tube 4 is somewhat relieved and the briquette column may then be advanced without requiring the application of excessive power as otherwise would be required.

Referring more particularly to Fig. 8, it will be understood that the full travel of the ram 13 is represented by the distance between the lines 10 a and b. When the ram is fully retracted, a charge of straw is moved downwardly, under action of the feed ram 6 into tube 4. Then, as the ram 13 advances, it cuts off that volume of straw in tube 4 between the limit lines a and c in Fig. 8, and compresses it into a briquette, which is designated by that portion of material between lines d and b.

At the instant the end surface of the ram on a compression stroke reaches the extent of travel 20 designated by line d, the valve piston 31 moves to "closed" position, and thus pressure is cut off from the clamp chamber 25, and the relief is opened, thus allowing the clamp to release, and the tube 4 to slightly expand. This expansion 25 releases the extreme pressure then frictionally holding the briquette column, and allows the column to be advanced, thus placing the formed briquette between the limit lines b and e. Then as the ram 13 is retracted, the valve piston 31 moves back to "open" position and pressure is again admitted to the clamp chamber. As the ram 13 reaches its retracted position, the tube 4 again receives a fresh charge of straw for compression as advanced by the feed ram or rod 6.

35 The timing of the feed ram 6 with the ram 13 is through a driving connection with shaft 6 comprising a horizontal shaft 60, which, at one end has a geared connection designated at 61, with shaft 19, whereby it is caused to rotate therewith, and at its other end has a geared connection, as at 62, with the shaft 8. The crank shaft 8 has throws 8a and 8b at opposite ends connected by rods 64-64' with the opposite ends of a cross head 65 on the upper end of rod 6 to cause it to reciprocate in timing with ram 13 and in such manner that, as the ram 13 is retracted, the rod 6 moves down on a compression stroke, thus to advance a charge of material into tube 4 as the ram 13 is retracted.

50 To prevent possible damage to the machine in the event of clogging of the tube 3 or hopper, the connection between the ram 6 and rods 64-64' is yieldable as noted in Fig. 1 and Fig. 6, wherein the rods 64-64' are provided with slots 66-66' at their upper ends and the ends of the cross head 65 are contained in these slots. Coiled tension springs 68-68' surround the rods 64-64', being fixed thereto as at 68a, and to the cross head 65 at 65a.

60 Where a low vacuum pump is used in conjunction with the machine, a housing is used which surrounds the slotted portion of the vertical feed tube and also the back portion of the horizontal compression tube up to the first reinforcing ring. This housing is attached to the suction end of the vacuum pump and has a clean-out hole in the bottom thereof to remove any comminuted material which is forced outwardly through the slots. When this arrangement is used, a briquette of extremely high quality is produced without the use of an extremely high vacuum. However, many materials may be satisfactorily briquetted without the use of this enclosing vacuum housing; the air included in the comminuted material being extripated by means

of simple pressure through the slotted tubes. It will be understood that the vacuum seal is formed by a solid section of the feed tube above the slots and a second vacuum seal being formed in the main compression tube by a solid section of the main compression tube which is inside the first confining ring. In each case, the packed material acts to prevent the ingress of air into the vacuum housing.

It has been shown to be old in the art of briquette manufacture to exclude the air from comminuted material by means of a flow of superheated steam therethrough. This process is described in U. S. Patent No. 1,453,988, issued to Mueller, May 1, 1923. It has been discovered, however, that the Mueller method is not satisfactory for the production of a briquette under the most ideal conditions. In general, these conditions consist of a comparatively high temperature, as, for example, 450° F. When superheated steam is used to expel the air from material to be briquetted at this very high temperature, the steam itself has a very great disruptive force, and, in fact, acts in very much the way that air would act upon compression of the briquette. This is due to the fact that vaporous water at a temperature of 450° F. exerts a pressure amounting to several hundred pounds per square inch. This, of course, causes an extreme disruptive action as the pressed briquette is released from a briquette machine.

A modification of the present invention comprises first heating the material to be briquetted to a very high temperature, such as 450° F., and then cooling the material to a considerable extent by blowing saturated steam at atmospheric pressure through the loose material thereby removing all air, thus substituting an atmosphere of condensable water vapor throughout the comminuted particles. When this procedure is adopted, it is found that there is no disruptive action due to the presence of the steam because of the fact that the material is cooled enough so that the vapor pressure of the steam is approximately atmospheric. This is due to two factors, the most important of which is comparatively low temperature of the material, and the second of which is the hygroscopic absorptive action of the material to be briquetted. This absorptive action tends to reduce the steam pressure quite materially as long as the material is not at an excessive temperature. Thus the air is removed by the saturated steam, but the steam itself exerts no disruptive force, so that a very solid briquette is formed. The chief advantage of this procedure, as compared to that described by Mueller, is that the finished briquette consists of material which has had its hygroscopic expansion factor destroyed by the high initial temperature of 400° F. to 500° F. Thus the briquette will remain solid even when exposed to moist conditions of the atmosphere. This is not true if the material had originally been heated to only 220° F., and then contacted with superheated steam of the same temperature.

For example, a wood briquette in which the material has been dried at 220° F. and then briquetted by Mueller's superheated steam process, has a linear expansion when exposed to extremely moist air, of approximately 3% of its linear dimensions. This amount of expansion will cause the material to fall apart and become a mere heap of comminuted sawdust. On the other hand, material which has been treated to an extremely high temperature of 400° F. to 500°

F. and then briquetted, after having been cooled considerably by the introduction of saturated steam, has a linear expansion factor of less than one-half of one per cent of its linear dimensions. This briquette will retain its solidity when it is exposed to extremely moist air.

When the air in a comminuted material has been expelled by atmospheric pressure saturated steam, as above described there is a small moisture content put into the briquette because of the steam which is absorbed by the comminuted material. This small moisture content is desirable because of the fact that it tends to balance the moisture content of the briquette with the moisture content which the briquette would naturally absorb from the atmosphere upon long standing. Thus the main part of the hygroscopicity of the material is destroyed by means of high heat, and what small moisture absorbing property that is left in the material is rendered impotent to cause any disintegration in the finished briquette upon long standing in the atmosphere.

With the machine so constructed, it will be understood that the reciprocating ram 6 will keep the tube 3 charged with material, and that the material will be advanced in a compressed condition into tube 4. Since the ram 6 operates in unison and in timing with the forming ram 13, it is understood also that the charges will be advanced from tube 3 into tube 4 while the ram 13 is in its retracted position. These successively advanced charges are all of the same volume and thus provide for the formation of briquettes of like size and density.

A feature of this feeding device is that the comminuted material is packed into tube 3 under considerable pressure and by reason of this pressure, the greater percentage of air is dispelled therefrom, and the charges are advanced in a substantial degree of solidity into tube 4 for final compression.

The clamp 12 in this instance is the means that governs the pressure under which the briquettes are formed for it is to be understood that with the column of formed briquettes held in tube 4 against advancement, the compression of material under action of the ram 13 will continue until the clamp releases the tube for slight expansion, whereupon the compression ceases and the entire column of briquettes is advanced by the pressure applied against the last finished briquette. In the present instance, the briquettes are formed under approximately 15,000 pounds pressure per square inch, and the release of the holding pressure for advancement of the column relieves the machine of approximately seven-eighths of the power that otherwise would be required.

The slotting of the forming tube further provides for escape of air under the final forming action from the material being compressed in the tube. Attention is also called to the fact that the tube 4 might be rectangular or of other cross sectional form to provide briquettes of desired shape.

The effectiveness of the feed devices for the exclusion of air from the comminuted material might be additionally increased by the injection of saturated steam into the base of the hopper through pipe connections as are indicated at 80 in Fig. 1.

The slotted pre-compression tube 3 shown in Fig. 1 acts as a metering device to regulate the size of the formed briquettes. These briquettes can be made larger or smaller by increasing or

decreasing the tension on the springs 68 and 68' shown in Fig. 6. As it is very important from the standpoint of a product which is to be merchandized in packages, that the packages be of uniform size, this feature in the present machine of an exact control of the size of the individual briquette is very desirable and of considerable commercial importance.

When the slotted main compression tube 4 is used with the application of steam at atmospheric pressure, it is desirable that a steam jacket 100 surround the back portion of this tube along that part within the compression zone a—b in Fig. 9, and that this jacket be filled with atmospheric pressure steam so that with each backward stroke of the ram 12, steam will be drawn into the compression tube instead of air. This will have the effect of eliminating any substantial quantities of air which would otherwise have to be expelled through the slots in the compression tube. In the bottom of this steam jacket, it is obviously necessary that there be a clean-out hole 101 for the removal of any comminuted material which might work through the slots.

Such machines are exceedingly effective for the formation of briquettes, and, by reason of their simplicity and comparative lightness, are especially desirable for portable use.

It is not intended that the invention be limited to the details disclosed herein, but that it be given an interpretation commensurate with the spirit of the invention.

Having thus described my invention, what I claim as new therein and desire to secure by Letters Patent is:

1. A briquette press comprising a forming tube, a feed tube opening into the forming tube, means operable to charge the feed tube with a column of comminuted material to be briquetted under air eliminating compression and to advance the charge while compressed progressively into the forming tube, and means operable intermittently to further compress the material as received by the forming tube from the feed tube into briquettes; said feed tube being provided along its length with openings for escape of air as eliminated from material incident to its compression in the feed tube.

2. A briquette press comprising a forming tube, a feed tube opening into the forming tube, means operable to charge the feed tube with a continuous column of material to be briquetted under air eliminating compression and to advance the column progressively into the forming tube, and means operable intermittently to further compress that part of the column of material received by the forming tube from the feed tube into individual briquettes; said feed tube being provided along its length with openings for escape of air as eliminated from material incident to compression of the material in the feed tube, and said forming tube being provided with openings for escapement of air dispelled from the material incident to formation of the briquettes.

3. A briquette press comprising a forming tube, a feed tube opening into the forming tube, means operable to charge the feed tube with a column of comminuted material, means for the introduction of saturated steam to the material prior to compression to expel the air therefrom prior to entering the feed tube, means to advance the column of compressed material progressively from the feed tube into the forming tube, and means operable to further compress the material in the forming tube into briquettes.

4. In a briquette press, a forming tube adapted to receive charges of material to be formed into briquettes, a ram reciprocally operable in the tube through a stroke of definite length for forming the briquettes and for the advancement of the formed briquettes as a continuous column along the tube; said tube being longitudinally divided into sections to provide for a limited diametric expansion and contraction of the tube, a hydraulic clamp housing enclosing the divided part of the tube and having a flexible inside wall contacting with the tube and means operable in timing with the reciprocal actions of the ram for delivery of a hydraulic pressure medium into the housing to cause contraction of the tube and for relieving the pressure in the housing to permit expansion of the tube.

WORTH C. GOSS.
